UNITED STATES PATENT OFFICE.

HANS GÜNTHER, OF AUGSBURG, GERMANY.

METHOD FOR MANUFACTURING STEEL BANDS, WIRES, OR THE LIKE ENVELOPED IN CELLULOID OR SIMILAR MATERIAL.

1,099,598.

Specification of Letters Patent.

Patented June 9, 1914.

No Drawing.

Application filed February 4, 1911. Serial No. 606,659.

To all whom it may concern:

Be it known that I, HANS GÜNTHER, engineer, a subject of the King of Bavaria, and residing at Augsburg, Germany, have invented certain new and useful Improvements in Methods for Manufacturing Steel Bands, Wires, or the like Enveloped in Celluloid or Similar Material, of which the following is a specification.

10 In manufacturing corset and dress steels made of strips of steel with celluloid covering these steel strips were hitherto wrapped in celluloid or a substitute therefor, in the same manner as this is the case with corset 15 steels wrapped in paper. The enveloping material will in this instance lie close to the steel strip. The finished product can therefore be only very slightly thicker and broader than the filling, namely by a few 20 tenths of a millimeter according to the thickness of the enveloping material. It is therefore necessary to use comparatively thick and broad steels, so as to obtain the customary dimensions of the covered article. It 25 has been proposed to place the filling between two plates or strips of the enveloping material, celluloid or the like, and to then unite these plates or strips with each other and the filling in known manner by heat and 30 a simultaneously applied pressure or by other known means. In these known processes it is necessary for the absolutely equally wide steel strips to be laid by means of templets, quite parallel and at equal 35 distances from each other, and held in such a position, until the cover plate of celluloid is placed over them and the whole is secured between the grooved press plates, if the fillings are not to shift before or during the 40 pressing process. With this process the width of the finished article will always depend on the width of the inlaid steel.

According to the present invention steel strips or steel wires of any section are covered with celluloid, celluloid substitute and other elastic materials or by a subsequent removal of the steel cores, seamless celluloid or other covers may be produced. According to the present method the steel strips are 45 also laid between two plates and pressed with these plates, but the spaces intervening the several steel strips are not left empty, as in the known methods, but are filled out

with strips of celluloid and the like. On a plate consisting of the respective covering 55 material, celluloid or the like, which is to form the bottom, is placed first a strip of celluloid then a strip of steel and so on one next to the other until the bottom plate is quite filled up. Now the whole is covered 60 with a second plate of enveloping material, celluloid and the like. The joining of the top and bottom and the intermediate strips to each other and with the steel cores is now carried out in known manner by heat and 65 pressure or by other suitable means. After the several parts have been joined to each other the composite plate thus produced is divided along the middle of the intermediate strips, so that the corset-, bodice-, and similar steels are obtained of the desired widths. 70

In place of a single strip of steel or a wire also two or more (double steels) may be employed as cores. The steel core may furthermore be rigidly attached to the enveloping material or it may be provided, that the core remains loose in the envelop. Lastly the present method allows of employing the core as a mandrel only, which is subsequently withdrawn in known manner after 80 the manufacture has been completed. By this means it will be possible to produce seamless tubes for paints and cosmetics, seamless hose and similar articles of celluloid or similar material. 85

I claim:

A method of enveloping elastic inserts in celluloid or similar materials, consisting in placing the elastic inserts in spaced relation upon a sheet of material, filling the spaces 90 between the inserts with strips of the enveloping material, said strips and insertions being of the same height, superposing a cover sheet of material pressing said sheets between plates under the action of a heating agent to an integral plate, dividing the plate thus formed into strips along the middle of said filling strips of material, and finishing the strips, substantially as herein described. 95

In testimony whereof, I affix my signature in the presence of two witnesses.

HANS GÜNTHER.

Witnesses:

WILHELM KRAPP,
CHAS. BORNGRAEBER.
